SWINGING PLATE VALVE CONSTRUCTION

Joseph W. Broome, North Sudbury, Mass., assignor to
The Oilgear Company, Milwaukee, Wis.

Filed May 17, 1957, Ser. No. 659,850

22 Claims. (Cl. 137—622)

This invention relates to an improved valve construction. Valves made according to my invention may be utilized to advantage in servomechanisms; they are also of particular utility in applications requiring the control of flow of corrosive and erosive fluids. My invention relates to an essentially frictionless valve of the swing plate type having power handling capabilities.

Many automatic control systems, e.g. servomechanisms, employ hydraulic pumps and hydraulic motors. These motors may operate in rotation or translation to drive their loads and may be constructed in any of several well-known forms, e.g. vane and piston-cylinder arrangements. Frequently the output of the motor, i.e. its position or speed, is controlled by a valve which regulates the flow of hydraulic fluid to it. These valves are generally actuated in accordance with error signals in the form of electrical voltages or currents developed by comparing the output performance with a command signal. They may be of the so-called three-way or four-way type depending upon the application. A four-way valve has the two hydraulic power outputs connected to the motor, the valve serving to switch the incoming hydraulic stream to one or the other of the outputs to determine the direction in which hydraulic force is to be applied to the motor. Three-way valves, on the other hand, have but one control line connected to the motor and thus are adapted to drive the motor in but one direction, the force required to return the motor being supplied by a spring, gravity, or other appropriate means.

To be efficiently employed in servo systems, these valves should be capable of controlling large hydraulic power in response to a minimum input signal; additionally they should be capable of fast response to an input signal. The power output is proportional to the product of the pressure and flow rate of the hydraulic fluid passing therethrough. Thus to control large loads, a valve must withstand high pressures and provide, upon actuation, valving orifices of sufficient area to permit the desired relatively large flow. In general, higher pressures requiring lower flow rates are desirable in order to minimize the size of the system components. Moreover, higher pressure requires less motion of the moving parts of the controlling valve, minimizing the effects of valve inertia, etc. The power required to actuate the valve, which may be derived hydraulically from a ram or electrically from a torque or force motor, is a function of such factors as inertia, valve friction, hydraulic pressure, and flow rate. Of these factors inertia is minimized by keeping the mass of the moving parts low, and the effects of pressure and flow may be compensated for by proper shaping of the valve chambers. Friction on the other hand has been a serious problem in commercially practicable valves. It degrades both the linearity of the orifice area—actuating force curve and the sensitivity of such valves.

Prior to my invention the hydraulic spool-type servo valve was most widely used. It consists of a cylinder

2

and a piston-like spool adapted for translatory controlling motion therein. Such spools have circumferential lands with chambers therebetween, the cylinder being similarly shaped with chambers and lands cooperating with those in the spool. Movement of the spool displaces the lands thereon from the cylinder lands to form orifices through which the valved fluid flows. Such orifices allow the hydraulic fluid to pass through various chambers in the valve between a hydraulic pump and a hydraulic motor. Valves of this type are costly to manufacture, particularly since they require close tolerance machining of the interior portions of a small diameter cylinder. Moreover, they are subject to frictional forces between the spool and cylinder. Further, minute solid particles carried in the hydraulic stream tend to lodge between the moving and stationary members of the valves, increasing friction and causing sticking. These particles thus increase valve hysteresis; they increase the actuating force required for a measurable change in flow rate, and they make it difficult for the valve to reach the null position, i.e. position of minimum flow, because the restoring force is least at this point. Therefore successful spool type valves are frequently driven by hydraulic actuators in turn controlled by torque motors instead of directly by the torque motors themselves. This increases the response time of the systems and also introduces additional non-linearities tending toward system instability.

The suspended plate valve appeared in an attempt to eliminate some of these undesirable characteristics inherent in the spool valve. It may have a mechanical configuration similar to that of the spool type, except that the lands and chambers are formed with flat rather than cylindrical surfaces. A valve plate having lands and chambers cooperating with those of a stationary valve block may be made to move over the block in its valving function with minimum friction principally because of the separation of plate and block caused by the pressure of the fluid therebetween. Prior to my invention this pressure was counteracted by the compression of support members from which the plate was suspended. To prevent buckling of these members, they should be relatively thick, thus making deflection thereof and translation of the valve plate difficult. The flow rate which may be obtained practicably by such a valve under high pressure is therefore low, as is the resultant power handling capability. Suspended plate valves of this design also tend to catch suspended particles between plate and block to such degree that sticking, with its attendant effects, is a serious problem.

As will be seen hereinafter, there are many other applications in addition to servomechanisms in which valves made according to my invention may be readily utilized. In many cases it is desirable to control flow of hot gases under high pressure. Prior to my invention the erosive actions of such gases caused inordinate wear on valves used for such control. Moreover, a serious problem is encountered in maintaining sufficiently tight seals for such gases while retaining relative ease of valve control.

It is often desirable to control the flow of a slurry containing suspended particles of various sizes. With prior valves the increased friction caused by such particles often prevented sufficient closure.

Accordingly, it is an object of my invention to provide an improved valve having a minimum of friction between moving and stationary parts. It is another object of my invention to provide a valve of the above character whose operation is substantially unaffected by particles suspended in the valved fluid. It is a further object of my invention to provide a valve of the above character having a large power handling capability. Yet another object of

my invention is to provide a valve of the above character requiring a minimum actuating force. It is a still further object of my invention to provide a valve of the above character which resists corrosion and erosion by the valved fluid. Yet another object is to provide an improved valve assembly incorporating a valve of the above character. It is a further object of my invention to provide a valve of the above character capable of efficient use as a controlling element in hydraulic servo systems. Another object of my invention is to provide a valve of the above character which is relatively low in cost and simple to manufacture. A final stated object of my invention is to provide valves of the above character adapted for either three or four-way operation. Other objects of my invention will in part be obvious and will in part appear hereinafter.

The invention accordingly comprises the features of construction, combinations of elements, and arrangements of parts which will be exemplified in the constructions hereinafter set forth, and the scope of the invention will be indicated in the claims.

For a fuller understanding of the nature and objects of the invention, reference may be had to the following detailed description taken in connection with the accompanying drawings in which:

Figure 1 is a schematic representation of my four-way valve and associated components as connected for use in a typical servo system.

Figure 2 is a side elevational view, partly in section, of a four-way valve made according to my invention showing its mounting within the valve housing.

Figure 3 is a top plan view, partly in section, taken along the line 3—3 of Figure 2.

Figure 4 is a vertical sectional view taken along the line 4—4 of Figure 3.

Figure 5 is a fragmentary vertical sectional view of a four-way valve taken along the line 5—5 of Figure 4.

Figure 6 is a view of the above block taken along the line 6—6 of Figure 4.

Figure 7 is a vertical sectional view similar to Figure 4 and depicting a three-way valve which is a second embodiment of my invention.

Figure 8 is an enlarged fragmentary vertical sectional view similar to Figure 4 and showing a third embodiment of my invention including a pressure compensating structure, and

Figure 9 is a fragmentary sectional view taken along line 9—9 of Figure 8.

Referring to Figure 1, my four-way swing plate valve may have a valve plate 2 for movement over a valve block generally indicated at 4 in response to the motion of a torque or force motor 6 transmitted to the plate through suitable linkage generally indicated at 8. The valve is connected to regulate the flow of hydraulic fluid from a pump 10 to a hydraulic motor 12. Thus fluid from the pump enters a pressure chamber 14 by way of a line 15 and passes into a chamber 16 in plate 2 bounded by lands 18 and 19. With the plate in the full line position of Figure 1, land 18 engages a land 20 in block 4 to prevent flow in that direction. Land 19 is thus disengaged from land 21 permitting fluid to pass from chamber 16 into a control chamber 22 in block 4 and thence to the motor 12 through a line 24. It leaves the motor to return to a second control chamber 26 in the block through a line 28. The flow continues into an exhaust chamber 30 bounded by lands 18 and 32 through an orifice formed by the disengagement of land 18 from a block land 33. It may then return to the pump 10 through an exhaust chamber 34 and a line 36. Accordingly the flow is to the motor 12 through line 24 and to exhaust through line 28.

The flow to motor 12 may be halted by energizing the torque motor 6 to move valve plate 2 to the left (Figure 1) to the dotted line null or center position. Lands 18 and 19 then block chambers 22 and 26 from pressure

chamber 14. Further leftward movement of the valve plate will cause reversal of the direction of flow to the motor 12. Land 18 will then be disengaged from land 20 to allow communication between chambers 14 and 26 through chamber 16, and lands 19 and 21 will be engaged to prevent flow to chamber 22. Engagement of lands 18 and 33 will cut off chamber 26 from chamber 30; and disengagement of land 19 from a block land 37 will permit flow between chamber 22 and an exhaust chamber 38 by way of a chamber 40 in plate 2 bounded by lands 19 and 42. The fluid then returns to the pump 10 through a line 44. Accordingly, the flow is to motor 12 through line 28 and from the motor to exhaust through line 24. The direction of motion of the hydraulic motor 12 may thus be changed at will by moving the valve plate 2 over the block 4 in response to appropriate input signals to the torque motor 6. The mode of operation of all four-way valves of the sliding plate type is similar to that described above, although the particular land-chamber configuration thereof may vary.

Prior to my invention the sliding plates of these valves were supported by depending resilient members acting in compression against the hydraulic forces in chambers 14, 22, and 26. Compression of these members caused by such forces aids in providing clearance between the plate and block to eliminate friction therebetween, the supporting members bending upon the actuation of the valve to act like hinges for the plate. To prevent buckling under pressures of upwards of a thousand p.s.i. or more, these members must have substantial cross sectional areas. However, when they are so heavily constructed it is difficult to deflect them even the few thousandths of an inch necessary to operate this type of valve. The available power output, as well as the power gain, is insufficient for normal operation as a direct controller.

The present invention overcomes this problem by supporting the valve plate from members or supports which are in tension and thus are not subject to buckling. These supports may be much thinner than the compression members formerly used; and thus they are relatively easily deflected for plate movement upon actuation of the valve. Since the valve plate may thus undergo greater excursions with less actuating force, the available flow rate is materially increased as are the power handling capabilities and power gain of the valve. My valve has other advantages which will be described, e.g. its operation may be made relatively independent of particles suspended in the fluid passing through it and it has improved stability in the null position.

More particularly, as seen in Figure 2, my valve assembly may include a base 46 and a housing 48 suitably secured thereto. As seen in Figures 2 and 3, a pair of foot blocks 50 and 52 are rigidly secured to opposite sides of the valve block 4 in any suitable manner such as brazing or welding and fastened to the base 46 by suitable screws 54. The valve plate 2 is supported above the valve block by a pair of supports 56 and 58. These supports are preferably thin sheets of steel welded at their upper ends to a pair of brackets 57 and 59 which are suitably secured to the top of plate 2 as by screws 61. The lower ends of the supports may be secured to a pair of foot blocks 60 and 62 affixed to the base 46 by screws 64. Thus the plate 2 is supported above the block 4, and there is a slight clearance between the opposing faces of these parts to eliminate friction upon movement of the plate. This clearance is exaggerated in the drawings for purposes of illustration. Further, the supports act as leaf springs tending to restore the valve plate 2 to the center or null position upon deflection thereof by the torque or force motor 6.

As best seen in Figures 4 and 6, chambers 14, 22, and 26 are preferably rectangular slots formed in the upper surface of the block and extending crosswise thereof. They may communicate with a hydraulic pump and motor through passages 66, 68, and 70 connecting with lines

(not shown) suitably attached to the base 46. The exhaust chambers 34 and 38 preferably extend across the valve block 4 in similar fashion. The upper face of the valve block 4 is preferably as flat and smooth as practicable.

The valve plate 2 has its lands and chambers arranged to cooperate with those of the block 4. Thus the chambers 16, 30, and 40 and lands 18 and 19 extend crosswise of the plate which preferably is the same width as the block 4. Accordingly, the chambers and lands in the plate and block are preferably coextensive and exactly opposed when the valve is in its center or null position. More particularly, lands 18 and 19 are positioned to block the chambers 22 and 26 when the plate is in the null position as can be seen in Figure 4. In such position exhaust chambers 30 and 40 are directly opposite chambers 34 and 38. Thus upon the slightest movement of the valve plate 2 by torque motor 6, an orifice connects chamber 16 to either control chamber 22 or 26. The other control chamber not so connected will be connected with its adjacent exhaust chamber. As will be described, the lands 18 and 19 may overlap or underlap, i.e., extend beyond or not quite cover, their corresponding control chambers, depending on the valve applications. Plate 2 may be secured to the linkage 8 extending therethrough by a nut 72 (Figure 4) and to the torque motor 6 by a nut 73. The torque motor in turn may be mounted in suitable fashion upon a standard 74 secured to base 46.

To prevent unwanted venting of fluid from the valve, the ends of chambers 14, 16, 22, and 26 are sealed with cover plates 76, 78, 80, and 82. As shown in Figures 2 and 5, these plates may be brazed, welded, or otherwise suitably secured to the sides of plate 2 and block 4. The upper edges of cover plates 80 and 82 and the lower edges of plates 76 and 78 are preferably coextensive with the upper face of block 4 and the lower face of the plate 2, respectively. It will be noted that they do not cover the ends of the exhaust chambers 30, 34, 38, and 40. Thus these chambers are vented directly to the exterior of the valve, and the fluid entering them from chambers 22 and 26 encounters essentially no back pressure. The fluid issuing from the exhaust chambers may thus be retained within the housing 48 and then withdrawn to a sump and pump for recirculation in a well-known manner.

As best seen in Figure 3, torque motor 6 may have an armature 81 conventionally mounted for motion between a pair of pole pieces 83 under the influence of a magnetic field developed by electrical coils (not shown). Thus 50 the armature may stroke valve plate 2 through its connection to linkage 8 at the nut 73. Since, as pointed out above, the valve plate supports 56 and 58 serve as restoring springs, no further springs for this purpose are required in the torque motor 6. It will be understood that for high power applications where the actuating force of a torque or force motor is insufficient for efficient operation, a hydraulic actuator may be used to stroke the valve plate 2.

Referring again to Figure 4, the fluid from a pump or other pressure source enters the pressure chamber 14 through passage 66 and then is conducted by chamber 16 to one of the control chambers 22 or 26 depending on the direction of actuation of torque motor 6 (Figure 2) and consequent position of plate 2. The fluid from 60 this chamber travels to the hydraulic motor and then returns to the other control chamber from which it passes into an exhaust chamber to be vented to the exterior of the valve, as previously described with reference to Figure 1. The flow of fluid through the valve substantially ceases when the valve plate 2 returns to the null position; supports 56 and 58 are continually urging the plate toward this position. Reversal of flow may be achieved by continuing movement of plate 2 beyond the null position.

For efficient operation in servo systems, the outer corners of the lands and chambers should be as square as possible to linearize valve characteristics. Moreover, the areas formed between the lands in the valve plate 2 and block 4 for fluid flow are nearly proportional to the valve plate displacement to either open position. Thus the flow rate may be made a substantially linear function of valve displacement, an important feature in servo systems.

10 Further, the orifices extend across the entire width of the valve, and therefore, for a given displacement of the valve plate there is a correspondingly large change in orifice area than with the configurations of prior valves; this makes possible a substantial increase in power gain. 15 Further, as pointed out above, the supports 56 and 58, being in tension, may be made from relatively thin stock and thus are readily deflected by the valve actuator. Consequently, this valve is capable of a high power output with a lower actuating force.

20 The clearance between the valve plate 2 and block 4 may vary depending upon the particular application. For example, in hydraulic servo systems it may run from .0002 inch to .003 inch depending upon the particular fluid, the size of suspended particles, etc. It will be noted that the clearance may be adjusted after machining of the cooperating faces of the valve plate and block. Thus if there is insufficient clearance, the bottom of the block may be ground to lower the upper surface thereof, and if it is too great the bottoms of the supports 56 and 58 and the blocks 50 and 52 attached thereto may be ground to lower the bottom surface of plate 2.

25 The extent of overlapping of the chambers 22 and 26 by lands 18 and 20 also depends upon the application of the valve. An exact match, i.e., zero overlap and zero underlap, may be desirable in many servo applications. Where the valve is to control the flow of gases, a substantial overlap together with a minimum clearance between the valve plate and block may be required to provide an effective seal in the null position. On the other hand where slurries carrying solid particles of considerable size are to be valved, it may be desirable to have a certain amount of underlap together with greater clearance between plate and block to prevent sticking and also to minimize the valve dead band, i.e., the amount of valve plate movement from the null to the open position.

30 It will also be seen that the materials forming the valve plate and block may vary depending upon the valve application. Thus aluminum may be satisfactory at low pressures while higher pressures may require a stronger material such as steel. Where corrosive fluids are to be valved, the portions of the valve exposed thereto may be coated with a non-corroding substance or the valve plate and block may be made of such material. When the flow of hot erosive gases is to be controlled, the plate and block may be molded of or glazed with ceramic material resistive to such wear. In prior valve constructions the use of such materials was practically impossible because of the difficulty of machining them to the required configurations. The present valve may in many cases be fabricated without final machining operations. Where extremely close tolerances are required, the configurations of the parts readily permit grinding for shaping or even hardened ceramics.

35 The operation of the present valve is relatively independent of particles suspended in the valved fluid because the plate supports 56 and 58 act in tension. Such particles have hindered proper operation of prior valves by lodging between the surfaces of the moving and stationary parts to cause sticking or friction therebetween. This can be particularly troublesome when it is attempted to return the valve to the center or null position. In such case the signal may be applied to the valve actuator at a minimum level, and the restoring force may 40 thus be insufficient to accomplish a complete null. Re-

referring to Figure 4, it will be apparent that when the valve plate 2 is displaced to either side of the null or center position, it swings in an arc on supports 56 and 58 and thus moves downwardly toward the block 4 while remaining parallel thereto, thus reducing the plate block clearance. Conversely, as the plate swings back to the center position such clearance increases. Thus as the plate returns to the center position the clearance between the lands increase, and particles which may have lodged therebetween are released. This diverging movement of the parts thus inhibits sticking, and the valve returns to the null or dead center with minimum applied force.

The present valve has inherent stability in the null position markedly exceeding anything achieved by sliding plate valves using compressional valve plate supports. The pressure in the various chambers, particularly that in chamber 16 which is continuous during operation, pushes the plate 2 away from the block, tending to increase the clearance therebetween. As it is furthest from the block in the null position, this pressure constantly urges the plate to remain in that position. With compressional supports the reverse is true, i.e., the clearance is greater away from the null position with the fluid tending to displace the plate slightly to either side thereof. Resulting instability may cause drift of the hydraulic motor and oscillatory conditions in the entire system.

In certain applications the pressure supplied to chambers 16, 14, 22, and 26 may be high enough to bow the central portion of the plate upwardly, increasing substantially the plate block clearance and hindering effective control. In Figures 8 and 9 there is illustrated a modification of my valve to be used with such high pressure ranges. As shown therein, a pair of blocks 84 and 86 may be suitably secured to the sides of the valve block 4 to seal chambers 14, 22, and 26 in the manner of cover plates 80 and 82 of Figure 5. Bolts 88, threaded into blocks 84 and 86, extend through a yoke generally indicated at 90 extending over the top of plate 2. Yoke 90 includes vertical flanges 92 and 94 extending therefrom and a top 96; these flanges are spaced from plate 2 and plates 76 and 78, and the top is spaced from plate 2 as indicated at 96a (Figure 9). It will be understood that some of these space dimensions are exaggerated in the drawings in the interest of greater clarity. The valve plate may have a pair of chambers 98 and 100 opening toward the bottom surface of yoke 90 and connected to chamber 16 by passages 102 and 104. Thus in operation chambers 98 and 100 are under the same pressure as that in chamber 16, i.e., the output pressure of pump 10 (Figure 1). This pressure exerts a downward (Figure 8) force in chambers 98 and 100 to offset the upward bowing force. It will be apparent that the areas of chambers 98 and 100 may be set to balance out part or all of the upward (Figures 8 and 9) forces in chambers 16, 22, and 26 depending upon the results desired in a particular application.

There may be some leakage of fluid between plate 2 and yoke 90. However this flow comes directly from the pressure source via chambers 14 and 16 and therefore it will not effect valve operation. Thus the valve plate 2 may be of relatively thin light material with low inertia and yet maintain proper spacing from block 4 for efficient operation.

In Figure 7 I have illustrated a three-way valve made according to my invention. As shown therein the valve has a cooperating valve plate 106 and valve block 108, the valve block being suitably secured to a base 110 by supports 112 and 114 secured thereto. Supports 112 and 114 are secured to the base by blocks 116 and 118 and bolts 120 extending therethrough. Suitable linkage generally indicated at 122 may be provided to connect the valve plate to a motor such as motor 6 (Figure

1). Thus plate 106 may move over block 108 to regulate the flow of fluid through the valve in the manner described above.

More particularly, block 108 has a pressure chamber 124, a control chamber 126, and an exhaust chamber 128. Valve plate 106 has a chamber 130 bounded by lands 132 and 134 and an exhaust chamber 136 bounded by lands 134 and 138. Passage 140 is connected to the pressure source such as the pump 10 (Figure 1). In the null position land 134 is positioned to block control chamber 126 with overlap or underlap as desired. When valve plate 106 is deflected to the right, pressure chamber 124 is connected to control chamber 126 via chamber 130. The fluid then passes through a passage 142 to a hydraulic motor (not shown). This motor may take the form of a piston and cylinder with restraining spring, etc., working against the force of the incoming fluid. When plate 106 is moved to the left back to the null position with land 134 blocking chamber 126, further flow is prevented and the motor remains substantially locked as previously set. Upon further valve movement to the left, control chamber 126 is connected to exhaust chambers 128 and 136, and fluid from the motor will be vented therethrough. Accordingly the compressed spring in the cylinder will move the piston in the opposite direction.

It will be seen that the three-way valve of Figure 7 retains the various advantages of the four-way valve described above. It may be manufactured in the same manner and of the same materials, and further in high pressure systems it may be used with a pressure compensating system similar to that of Figures 8 and 9.

Thus I have described an improved valve construction which may be usefully employed in controlling fluids of various kinds including gasses and slurries. The valve has particular application in servo systems where it has the advantages of essentially frictionless operation, freedom from sticking, and inherent stability. Moreover, it is capable of high power output with comparatively low actuating force. My valve may be manufactured by well-known techniques and may be adjusted after initial machining to minimize the reject rate.

I have described both a three-way and a four-way valve and a pressure compensating arrangement which may be used with either valve. As noted, these valves may be made from a wide variety of materials depending upon application. While I have particularly described certain land and groove configurations, it will be understood that other configurations may be incorporated into these valves without departing from the scope of my invention. Moreover, it will be apparent that the plate supports and cooperating faces of the plate and block may, within the scope of my invention, take other forms than those specifically described above. Also, the movement of the plate may be rotary rather than translational, depending upon the particular forms employed.

It will thus be seen that the objects set forth above, among those made apparent from the preceding description, are efficiently attained and, since certain changes may be made in the above constructions without departing from the scope of the invention, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

I claim:

1. In a valve construction, the combination of a valve block, a plate associated with said block, said plate and block having opposing surfaces with valve chambers formed therein, said chambers being so shaped as to control fluid under pressure upon relative movement of

said surfaces substantially along each other, a member interconnected with said block and adapted to urge said plate against said block substantially only under tension, said tensionally acting member being adapted to yield to permit said relative movement of said surfaces and being substantially non-extensible in a direction coinciding with that of said tension.

2. A valve of the flat face type for controlling the flow of fluid under pressure, said valve comprising members with opposed faces having land and chamber portions and single supporting means rigidly connected to one of said members and rigidly connected to the other of said members, said means being nonextensible and subject substantially only to tension by the pressure of said fluid tending to separate said members, said supporting means being adapted to yield to permit said members to move relative to each other, thereby to control the flow of said fluid.

3. The combination defined in claim 2 including resilient means opposing said yielding of said supporting means.

4. A valve for receiving fluid under pressure, comprising members with opposed faces having land and chamber portions cooperating to control fluid flow, relative movement of said faces along each other controlling said flow, means for admitting said fluid into at least one of said chamber portions whereby said pressure of said fluid tends to separate said members, means supporting one of said members for movement of its said face along the face of the other said member, said supporting means acting only in tension in a direction transversely of said faces and being non-extensible in such transverse direction and being resilient in a direction parallel to said faces.

5. In a valve construction, the combination of a valve block, a plate associated with said block, said plate and block having cooperating faces so shaped as to control fluid under pressure upon relative movement thereof along each other, a member supporting said plate in closely spaced relationship with said block, means securing one end of said member to said plate, and means securing the other end thereof to said block, said member being adapted to act only in tension against said pressure and further adapted to yield in a direction permitting said relative movement of said cooperating faces.

6. The combination defined in claim 5 in which said member is resilient in the direction of said relative movement.

7. In a valve construction, the combination of a valve block, a valve plate disposed with a face thereof closely spaced from a cooperating face of said block, a cooperating land and groove in said faces adapted to valve a fluid upon relative movement of one face along the other, means adapted to introduce said fluid between said plate and block, whereby pressure of said fluid may urge said plate and block apart, means supporting said valve plate adapted to act only in tension against said pressure, and means securing said supporting means to said plate and block for movement therewith, said supporting means being also adapted to yield to permit said relative movement of said faces.

8. The combination defined in claim 7 in which one end of said supporting means moves relative to the other end thereof upon relative movement of said faces.

9. In a valve construction, the combination of a valve block, a valve plate disposed with a face thereof closely spaced from a face of said block, means supporting said plate for movement along said block, means securing said supporting means to said plate and block, a cooperating land and chamber arrangement in said plate and block adapted to valve a fluid upon said movement of said plate, means adapted to introduce said fluid between said plate and block, whereby pressure of said fluid may urge them apart, said supporting means acting only in tension

against said pressure and being resilient in the direction of movement of said plate and thereby being adapted to urge said plate to its initial position upon movement thereof.

5 10. In a valve construction, the combination of a valve block, a valve plate disposed with a face thereof closely spaced from and substantially parallel to a face of said block, a cooperating land and chamber arrangement in said plate and block adapted to valve a fluid upon movement of said face of said plate along said face of said block, means adapted to introduce said fluid between said plate and block, whereby pressure of said fluid may urge the plate and block apart, a plurality of valve plate supporting members, means securing each of said members to said plate and said block, whereby said members act only in tension against said pressure, said members being resiliently deflectable, whereby said face of said plate may be resiliently moved substantially along said face of said block to valve said fluid.

20 11. In a valve construction, the combination of a valve block, a valve plate disposed with a first face thereof closely spaced from a second face of said block, a pressure chamber in said second face and a pair of control chambers therein on opposite sides of said pressure chamber, means forming passages connecting said chambers with the exterior of said block, a pair of lands on said first surface positioned and adapted substantially to block said control chambers when the valve is in the null position, a chamber in said second surface bounded by said lands and communicating with said pressure chamber, valve plate supports, means for securing said supports to said plate and said block, whereby said supports may act only in tension against force exerted by said fluid tending to separate said plate and block, relative translation of said first face along said second face and away from said null position permitting fluid to flow through said pressure chamber and said chamber in said plate and into a control chamber to effect the valving action of said valve.

40 12. The combination defined in claim 11 in which said supports are resilient in the direction of relative translation of said valve plate, whereby upon translation away from said null position the ends of said supports secured to said plate are deflected with respect to the ends thereof secured to said block, said deflection causing a force to be exerted by said supports on said plate and block tending to restore them to the null position.

13. The combination defined in claim 11 in which said chambers are substantially in the form of rectangular slots extending across said block and plate at right angles to the direction of relative motion thereof, and including means sealing the ends of said chambers to prevent the flow of the valved fluid therefrom.

55 14. The combination defined in claim 11 including a pair of exhaust chambers in said plate bounded on one side by said lands, said lands being substantially coextensive with their corresponding control chambers, whereby upon relative translation of said plate away from said null position one of said control chambers may communicate with said chamber in said valve plate and the other control chamber may communicate with its adjacent exhaust chamber.

60 15. In a valve construction, the combination of a valve block, a valve plate disposed with a first face thereof closely spaced from and substantially parallel to a second face of said block, a pressure chamber in said second face, means forming a passage between said pressure chamber and the exterior of said block, a control chamber in said block, means forming a passage connecting said control chamber with the exterior of said block, a land in said first face opposite said control chamber and substantially coinciding with the opening thereof in said second surface, means forming a connecting chamber in said valve plate bounded on one side by said land and communicating with said pressure chamber, valve plate supports secured to said valve plate and said valve block, whereby

said supports may act only in tension against force of the valved fluid tending to separate said plate and said block.

16. The combination defined in claim 15 in which, upon translation of said valve plate with respect to said block to valve said fluid, the ends of said supports secured to said plate are deflected with respect to the ends secured to said block, said supporting members being resilient in the direction of said translation.

17. The combination defined in claim 15 in which said chambers are in the form of rectangular slots extending across said plate and block and substantially at right angles to the direction of said translation, and which includes means sealing the ends of said chambers to prevent escape of the valved fluid therefrom.

18. The combination defined in claim 15 including an exhaust chamber in said plate bounded on one side by said land.

19. In a valve construction, the combination of a valve block, a valve plate disposed with a first face thereon closely spaced from a second face on said block, a pressure chamber in said second face and a pair of control chambers therein on opposite sides of said pressure chamber, means forming passages connecting said chambers to the exterior of said block, a pair of lands on said first face positioned and adapted substantially to block said control chambers when the valve is in the null position, a chamber in said first face bounded by said lands and communicating with said pressure chamber, said chambers being substantially in the form of rectangular slots extending across said block and plate at right angles to the direction of relative motion thereof, means for sealing the ends of said chambers to prevent the flow of fluid therefrom, valve plate supports, means for securing said supports to said plate and said block, said supports being adapted to act only in tension against force exerted by the valve fluid tending to separate said plate and block, relative translation of said first and second faces away from said null position permitting fluid to flow through said pressure chamber and said chamber in said plate and into a control chamber to effect the valving of said fluid, said supports being resilient in the direction of relative translation of said faces, whereby upon displacement from said null position the ends of said sup-

ports secured to said plate are deflected with respect to the ends thereof secured to said block, said supports being resilient in the direction of said relative movement and adapted thereby to exert a force on said plate and block tending to restore them to the null position.

5 20. In a valve construction, the combination of a valve block, a valve plate disposed with a first face thereof closely spaced from a face of said block, means supporting said plate for movement along said block, means securing said supporting means to said plate and said block, a cooperating land and chamber in said plate and block adapted to valve a fluid upon said movement of said plate, means adapted to introduce said fluid between said plate and block, whereby pressure of said fluid may urge them apart, said supporting means acting only in 10 15 tension against said pressure, a second face on said plate opposite said first plate face, a chamber formed in said second face, means forming a passageway between said first face and said chamber, a pressure plate closely spaced from said second face, means securing said pressure plate to said valve block, whereby pressure of said fluid between said plate and block is transmitted into said chamber in said second face to act between said pressure plate and valve plate, thereby to reduce said force urging said valve plate and block apart.

25 21. The combination defined in claim 9 in which said supporting means is non-extensible in the direction of said tension.

20 22. The combination defined in claim 20 in which said supporting means is adapted to yield to permit said movement of said plate along said block.
